UNITED STATES PATENT OFFICE.

MALCOLM W. LONG, OF HARRISBURG, PENNSYLVANIA, ASSIGNOR TO THE PENNSYLVANIA STEEL COMPANY, OF PHILADELPHIA, PENNSYLVANIA, A CORPORATION OF PENNSYLVANIA.

RAILWAY-SWITCH LOCK.

SPECIFICATION forming part of Letters Patent No. 789,163, dated May 9, 1905.

Application filed July 28, 1904. Serial No. 218,456.

To all whom it may concern:

Be it known that I, MALCOLM W. LONG, a citizen of the United States, residing at Harrisburg, in the county of Dauphin and State 5 of Pennsylvania, have invented certain new and useful Improvements in Railway-Switch Locks, of which the following is a full, clear, and exact description, reference being had to the accompanying drawings, of which—

10 Figure 1 is a plan view; Fig. 2, a side elevation; Fig. 3, a section on line $\alpha\alpha$, Fig. 1.

This invention relates to what are known as "ground - lever railway - switches," and I show in the drawings a well-known type of 15 such switches and stands to which my improvement is applied, although it may be applied to other styles of ground-levers.

The object of the invention is to provide an improved means for locking the switch-point in the closed position, which shall also act as a detector to indicate the presence of a 20 stone or other obstruction between the switch-rail and the stock-rail when the switch is attempted to be thrown from the open to the 25 closed position.

The precise nature of the invention will appear from the following description, reference being had to the drawings.

1 is one of the stock-rails; 2, one of the 30 movable switch-rails; 3, the bar connecting the two switch-rails.

4 is the switch-stand, in which the vertical shaft 5 is journaled and has at its lower end a crank 6, to which is pivoted one end of the 35 rod 7, that is connected to the end of bar 3. Mounted on the shaft 5 is a segment-gear 8, that engages a bevel-gear 9 on a horizontal shaft 10, to the free end of which is secured the weighted lever 11 for operating the switch.

40 When the lever is in the closed position—that is, when the switch is closed, as in the drawings—this lever rests in a depression or slot 12 of a block or pillar 13 (that is spiked to the tie) and is locked in that position by means 45 of a suitable catch 14.

The foregoing construction being well known requires no further description.

In carrying out my invention I connect to the switch—in the present instance to a stiffening-bar 15, connecting the points thereof—a 50 rod 16, whose free end portion 17 is widened vertically and is adapted to slide longitudinally in an opening or guideway 18, Fig. 3, in the block 13. The free end portion 17 of said rod is provided with a vertical slot 19, 55 adapted to neatly receive the lever-arm 11 when the slot is in line vertically with the latter. The position of this slot is such, however, that it will not be in line with the lever-arm except when the switch is in the closed 60 position, and when in that position the lever brought down into the slot locks the switch directly in place, while the catch 14 locks the same indirectly by preventing the lever from rising. Thus it is obvious that the switch- 65 man will see at once when he attempts to lock the switch in place and the lever cannot enter the slot 19 of rod 16 the switch has not reached the fully-closed position, thus indicating that either the lever has not been carried down a 70 sufficient distance or that there is some obstruction that prevents closure of the switch, and so prevents the rod 16 from moving the required distance to carry its slot 19 into registry with the lever-arm 11. For the purpose 75 of taking up wear, &c., I would usually make the rod 16 longitudinally adjustable. In this instance I accomplish this by threading the end thereof that is connected to the bar 15, as seen in Figs. 1 and 3, and screw onto such 80 threaded end a nut 20, having a projection or projections 21, that are pivotally secured to a lug 22 of said bar 15 by a suitable bolt 23. When it is desired to shorten or lengthen, as the case may be, the rod 16, the bolt 23 is 85 withdrawn and the nut 20 is screwed in the proper direction until the rod 16 is of the desired length, when the parts are reconnected.

Having thus described my invention, I claim as new and desire to secure by Letters Patent— 90

1. The combination in a railway-switch, of the movable switch - rails, a rod connected thereto, a lever for actuating said switch-rails, and means whereby said lever is adapted to

lock said rod against longitudinal movement when the switch is in the closed position, substantially as and for the purpose set forth.

2. The combination in a railway-switch, of 5 the movable switch-rails, the rotatable lever, mechanism intervening between said switch-rails and said lever whereby the switch is adapted to be opened and closed by means of said lever, and means for locking the switch in 10 the closed position comprising the block having the slot adapted to receive said lever, and the rod connected to said switch-rails and extending through said block, and having the vertical slot adapted to register with and receive said lever only when the switch is in the 15 closed position, substantially as and for the purpose set forth.

3. The combination in a railway-switch, of 20 the movable switch-rails, the rotatable lever, mechanism intervening between said switch-rails and said lever whereby the switch is adapted to be opened and closed by means of said lever, and means for locking the switch in closed position comprising the block having 25 the slot adapted to receive said lever, and the rod connected to said switch-rails and extending through said block, and having the vertical slot adapted to register with and receive said lever only when the switch is in the 30 closed position; together with means for locking down said lever when entered into said slot, substantially as and for the purpose set forth.

4. The combination in a railway-switch, of

the movable switch-rails, the rotatable lever, 35 mechanism intervening between said switch-rails and said lever whereby the switch is adapted to be opened and closed by means of said lever, and means for locking the switch in the closed position comprising the block 40 having the slot adapted to receive said lever, and the rod connected to said switch-rails and extending through said block, and having the vertical slot adapted to register with and receive said lever only when the switch is in 45 the closed position, together with means for adjusting the length of said rod, substantially as and for the purpose set forth.

5. The combination in a railway-switch, of 50 the movable switch-rails, the rotatable lever, mechanism intervening between said switch-rails and said lever whereby the switch is adapted to be opened and closed by means of said lever, and means for locking the switch in the closed position, comprising the rod connected 55 to said switch - rails and extending across the plane of movement of said lever, and having the slot adapted to register with and receive said lever only when the switch is in the closed position, substantially as and 60 for the purpose set forth.

In testimony whereof I have hereunto affixed my signature this 24th day of June, A. D. 1904.

MALCOLM W. LONG.
